(57) **CLAIM**

The ornamental design of a digital player, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a digital player showing my new design;

FIG. 2 is a front elevational view thereof;

FIG. 3 is a perspective view of a second embodiment of a digital player; and,

FIG. 4 is a front elevational view of FIG. 3.

The broken lines showing of environment are for illustrative purpose only and form no part of the claimed design.

1 Claim, 4 Drawing Sheets## FIG. 1

FIG. 2

FIG. 3

FIG. 4
